Attorneys

UNITED STATES PATENT OFFICE.

THOMAS H. ROSS, OF BROOKLYN, NEW YORK, ASSIGNOR OF ONE-HALF TO ROBERT K. STORY, OF BROOKLYN, NEW YORK.

WRENCH.

Application filed October 22, 1921. Serial No. 509,635.

This invention relates to wrenches, and my improvements are directed to a certain novel construction and interacting relation of object engaging parts whereby in the movement of a wrench in one direction an engaged object is gripped with increasing tenacity, utilizing the head portion of the wrench as a fulcrum, while in its opposite direction of movement the engaging parts of the wrench are relaxed to release and pass freely about the object.

With these ends in view my invention consists of a handle or stock in whose head portion there are pivotally mounted two complementary jaw portions which extend angularly, in parallel, slidably engaged relation, from the head portion, with opposed, object gripping surfaces, the pivotal axes for these jaw portions being arranged so that in the opposite movements of the latter their opposed gripping surfaces will be caused to approach and recede from an interposed work object in the performance of the wrench functions.

Other features and advantages of my invention will hereinafter appear.

In the drawing:—

Figure 1 is a side elevation of my improved wrench.

Fig. 2 is a rear view thereof.

Fig. 3 is a plan detail of one of the jaw elements.

Fig. 4 is a rear view of Fig. 3.

Fig. 5 is a plan view of the other jaw element, and

Fig. 6 is a rear view of Fig. 5.

In the figures the numeral 1 indicates the wrench handle, having the bifurcated head portion 2, carrying the transverse pivot pins 3, 4, upon which are respectively mounted the members 5, 6, which extend out angularly, in parallelism, from the head portion. The member 5 has an arcuate slot 7 by which it engages the pin 3, and is provided with an enlarged portion 8, with an upper gripping surface 9, and a curved under shoulder 10. It also has a finger piece 11 projecting from its rearward portion, one end thereof having a slot 12 engaging the pin 4, and its free end extending upwardly.

The member 6 has a shank portion 13 that is mounted on the pin 4, and a hook-like forward portion 14 with a lower, gripping

surface 15 opposed to the surface 9. The back of member 6 is grooved, at 15^a, to slidably contain the finger piece 11, a pin 16, which bridges the groove 15^a, engaging a slot 17 formed in the finger piece. Thus the members 5 and 6 are connected, for slidable relative movement as they rock individually about their respective pivotal axes 3, 4. A helical spring 18, lying in slot 17, between the upper end of the slot and the pin 16, normally urges the member 6 toward the member 5 for engaging purposes.

The showing of the wrench in full lines, Fig. 1, represents the wrench as swung in the direction indicated by the arrow for gripping and turning a work object engaged between the jaw-surfaces 9, 15; and the dotted position in the same view indicates the wrench as swung in the opposite direction to release the object preparatory to taking a fresh grip thereon.

It should be noted that in the gripping operation, to turn an interposed object, the shoulder 10 bears with cam-like action against the forward, curved surface 19 of head portion 2, which serves as the fulcrum for the gripping leverage employed, whereby no strain at all is imposed upon the pin 3.

The gripping surfaces 9, 15, while shown as angled for the reception of a hexagon nut or other object, may have other known gripping form, and may be of suitable character for engaging pipes.

The members 5, 6 may also be provided with lateral, angled lips or projections 20, 21, capable of entering depressed surfaces to function as a socket wrench. When so employed, however, the direction of movement of the wrench, in expanding and contracting its jaws, will be opposite to its direction of movement when gripping and releasing an engaged object.

From the foregoing description it will be obvious that my improved wrench is capable of operation in ratchet like manner, without the employment of a rack and pawl.

Variations within the spirit and scope of my invention are equally comprehended by the foregoing disclosure:—

I claim:

The combination, in a wrench, of a handle having a bifurcated head, and a pair of opposed jaws with shanks mounted respective-

ly on pivots disposed transversely of the lead, one jaw of the pair engaging its pivot by an arcuate slot, and having a rearward vertically slotted extension in slidably, inter-
5 fitting relation with the other jaw, the slot of the extension engaging the pivot upon which the shank of said last named jaw is

mounted, and the extension carrying a spring which urges the jaws toward each other.

10

Signed at New York, in the county and State of New York, this 13th day of October, 1921.

THOMAS H. ROSS.
